His Attorney.

UNITED STATES PATENT OFFICE

2,117,949

AMPLIFIER NEUTRALIZING SYSTEM

George W. Fyler, Schenectady, N. Y., assignor to
General Electric Company, a corporation of
New York

Application June 22, 1935, Serial No. 27,899

6 Claims. (Cl. 179—171)

5 My invention relates to electron discharge tube amplifiers, and more particularly to amplifiers of the type comprising two electron discharge devices connected in push-pull relation and provided with neutralizing circuits for preventing coupling between the input and output circuits due to the inter-electrode capacity existing in the tubes.

10 The use of neutralizing connections for preventing inter-electrode capacity coupling between the output and input circuits of a push-pull connected amplifier is well known. Such neutralizing connections usually comprise a neutralizing condenser connected between the control grid of 15 each tube and the anode of the other tube. It is desirable in amplifiers of this type to employ neutralizing condensers of fixed capacity, and this is particularly true in large power installations where the size of the condensers required 20 would make the cost of variable capacitors prohibitive. However, it has been found that if fixed neutralizing condensers be used some method of making minor adjustments must be provided if satisfactory neutralization is to be obtained. The 25 necessity for such adjustment is due primarily to variations in the characteristics of the tubes and condensers used in the construction of such amplifiers. Because of the manufacturing tolerances allowed in the manufacture of such apparatus it is difficult to obtain tubes and condensers having characteristics which are identical, and which conform exactly to the characteristics specified by the manufacturer. The effect of stray 30 electromagnetic and electrostatic coupling between the circuit leads in the input and output circuits of amplifiers of this type must also be neutralized if satisfactory operation is to be obtained.

35 In accordance with my invention the advantage of using fixed neutralizing condensers is retained and, at the same time, a means is provided whereby the minor adjustments necessary to obtain substantially perfect neutralization may easily be made.

40 It is an object of my invention to provide in an amplifier of the push-pull connected type an improved inter-electrode capacity coupling neutralizing system which includes an inductance in the neutralizing circuits which is adjustable to obtain substantially complete neutralization of 45 the inter-electrode capacity coupling between the output and input circuits of the amplifier.

45 It is a further object of my invention to provide in a push-pull connected amplifier a pair of 50 neutralizing circuits which include conductors

connected respectively in each of the circuits and arranged in adjustable inductive relation.

5 More specifically, it is an object of my invention to provide an arrangement of the above type in which portions of the neutralizing circuit conductors are arranged in inductive relation and mounted on a mechanical supporting structure whereby the portions of the conductors may be moved relative to one another to change the mutual inductance therebetween.

10 The novel features which I believe to be characteristic of my invention are set forth with particularity in the appended claims. My invention itself, however, both as to its organization and method of operation together with further 15 objects and advantages thereof will best be understood by reference to the following specification taken in connection with the accompanying drawing in which Fig. 1 shows an amplifier of the push-pull type having my invention embodied 20 therein, and Fig. 2 shows the equivalent bridge circuit of the circuit shown in Fig. 1.

25 Referring to Fig. 1 of the drawing I have shown an amplifier system connected in push-pull relation and arranged to be controlled by a source of 30 oscillations, as for example the output from a carrier wave oscillation generator, impressed on the primary winding of the transformer 1 and to supply its amplified output to the primary 35 winding of a coupling transformer 2. The secondary of the transformer 1 has its two ends connected respectively to the control grids of the 40 electron discharge tubes 3 and 4. The mid-point of the secondary of the transformer 1 is connected to a common cathode lead 6 of the tubes 3 and 4 through the ground connections indicated at 45. The respective anodes of the tubes 3 and 4 are connected to the two ends of the primary winding 50 of the transformer 2; which primary has its central point connected to the common cathode 55 lead 6 through the source of plate potential 7. The output circuit of the amplifier may be tuned to the operating carrier frequency by a variable condenser 8.

55 The operation of the above-described amplifier is well understood in the art and only a short explanation thereof is deemed to be necessary. Briefly described, as the oscillating input potential impressed on the primary winding of the 60 transformer 1 alternates between positive and negative values the tubes 3 and 4 alternately supply an amplified output current to the amplifier output circuit. The outputs from the two tubes are combined in the tuned output circuit includ- 65

ing the primary of the transformer 2 and are impressed on the secondary thereof.

In order to prevent any coupling between the input and output circuits of the system the neutralizing circuits 9 and 10 are provided which include respectively the fixed neutralizing condensers 11 and 12. It will be noted that the neutralizing circuit 9 is connected between the control grid of the tube 3 and the anode of the tube 4. In like manner the neutralizing circuit 10 is connected between the control grid of the tube 4 and the anode of the tube 3.

The effect of the two neutralizing circuits 9 and 10 is to supply currents to the control grids of the two tubes 3 and 4 which are equal in magnitude and opposite in phase to the currents flowing between the input and output circuits of the amplifier through the coupling therebetween formed by the capacity existing between the control grid and anode of each of the two tubes. In this manner interelectrode capacity coupling between the input and output circuits of the amplifier system is minimized.

It has been found in neutralizing systems of the type described, in which fixed neutralizing condensers are employed, that satisfactory neutralization cannot be obtained unless a suitable means is provided for making minor adjustments in the neutralizing circuits after the amplifier has been assembled and during its testing operations. This may be attributed to the fact that an accurate calculation of the neutralizing current necessary to satisfactory neutralization cannot be made. Manufacturing discrepancies in the construction of the elements used in the system, together with stray electrostatic and electromagnetic effects render an exact determination of the magnitude of the required neutralizing current practically impossible.

In order to overcome the above-described difficulty I provide a device for making minor adjustments which includes a pair of conductors 13 and 14 respectively forming a part of the two neutralizing circuits 9 and 10, the two conductors being arranged in inductive relation and suitably mounted for relative movement therebetween. I have shown the conductors 13 and 14 as comprising simply portions of the neutralizing leads and have indicated these conductors as being mounted on a supporting member shown diagrammatically at 15; the conductor 14 being adjustably mounted on the supporting member 15 by means of the two adjusting screws 16 and 17, and the conductor 13 being fixedly mounted thereon by means of insulators indicated at 18. It will of course be understood that any other suitable mounting arrangement may be employed and, further, that the conductors 13 and 14 may be arranged in any desired manner so long as they are maintained in inductively coupled relation.

With the above arrangement accurate neutralization of the system described may be obtained by moving the conductors 13 and 14 relative to each other to change the mutual inductance therebetween. As the mutual inductance is varied the amount of inductive reactance included in each of the neutralizing circuits is varied, thereby causing a variation in the value of the effective capacitive reactance in an opposite sense. Thus, if the inductance in each of the neutralizing circuits 9 and 10, is increased, the capacitive reactance is decreased by an equal amount and the total impedance in each of the two circuits thereby being lowered, the magnitude of the neu-

tralizing currents flowing to the control grids of the tubes is increased. In like manner, if the inductive reactance is decreased by decreasing the mutual effects between the conductors 13 and 14, the capacitive reactance in each of the circuits 9 and 10 is increased and the magnitude of the neutralizing currents flowing to the grids of the tubes 3 and 4 is decreased. It will of course be understood that the value of the mutual inductance between the conductors 13 and 14 and the required adjustment thereof are quite small, due to the high operating frequencies and the fairly close approach to complete neutralization normally obtained in a properly designed system. In this connection it will be appreciated that neutralizing condensers 11 and 12 having a capacity reactance value slightly higher than the calculated value should be used. This is necessary since the reactance of the coupled conductors 13 and 14 is substantially purely inductive and an increase or decrease in the value thereof simply determines the amount by which the capacity reactance of the condensers 11 and 12 is decreased.

The advantages of my improved neutralizing arrangement will be apparent from a consideration of Fig. 2 wherein I have shown the equivalent bridge circuit for the system shown in Fig. 1 and described above. In the bridge circuit of Fig. 2 the secondary of the input transformer 1 and the primary of the output transformer 2 are shown as being connected between the junction points of the equivalent bridge formed by the amplifier network. The equivalent grid-anode capacity of the tube 3 is represented by the condenser 19 and that of the tube 4 by the condenser 20. The neutralizing condensers 11 and 12 are included in the opposed arms of the bridge and the conductors 13 and 14, arranged in inductive relation, are in series with these two condensers.

It will be observed from an inspection of the equivalent bridge circuit that in the absence of the variable inductance formed by the inductively coupled conductors 13 and 14, the magnitude of the neutralizing currents would be fixedly determined by the value of the fixed condensers. However, by the introduction in the circuits of the adjustable inductive reactance formed by the inductively coupled conductors 13 and 14 the effective capacitive reactance in each of the neutralizing branches of the bridge may be varied until it is equal to the inter-electrode capacity of the tube being neutralized. Thus, if the inter-electrode capacities represented by the condensers 19 and 20 are actually lower than their rated values and the actual capacity of each of the condensers 11 and 12 is higher than the specified rating, the difference may be removed by introducing inductive reactance in the neutralizing circuits sufficient to cancel the required amount of capacitive reactance therefrom.

My improved neutralizing arrangement is particularly useful in those installations wherein it is desired that the amplifier shall operate at any one of several different frequencies. It has been found that when the frequency of the potential impressed on the input circuit of the amplifier is changed, a re-adjustment of the neutralizing system is necessary if exact neutralization of inter-electrode coupling is to be obtained. By the provision of the adjustable inductances formed by the conductors 13 and 14 the neutralization may be varied to obtain satisfactory operation over a wide band of operating frequencies.

My improved neutralizing system may be simply

and economically constructed and easily adjusted. Thus, the only element added to the amplifier structure is the mechanical supporting structure for maintaining the portions 13 and 14 of the neutralizing conductors in the proper physical relation.

While I have shown a particular embodiment of my invention, it will of course be understood that I do not wish to be limited thereto since many modifications in the circuit may be made, and I contemplate by the appended claims to cover all such modifications as fall within the true spirit and scope of my invention.

What I claim as new and desire to secure by Letters Patent of the United States, is:

1. An amplifier comprising a pair of electron discharge tubes each including an anode and a control grid, push-pull input and output circuits therefor having capacity therebetween requiring to be neutralized, a pair of neutralizing circuits each connected between a grid of one tube and an anode of the other tube, said neutralizing circuits each including a neutralizing capacitance means providing approximately the reactance value required for said neutralization, a pair of conductors connected respectively in each of said neutralizing circuits, said conductors being arranged in adjustable inductive relation, and means whereby the inductance included in each of said neutralizing circuits may be varied sufficiently to produce complete neutralization of said capacity.

2. An amplifier comprising a pair of electron discharge tubes each including an anode and a control grid, push-pull input and output circuits therefor having capacity therebetween requiring to be neutralized, a pair of neutralizing circuits each connected between a grid of one tube and an anode of the other tube, neutralizing capacitance means in said neutralizing circuits providing approximately the reactance required for said neutralization, each of said neutralizing circuits including a conductor, said conductors being inductively coupled, and means for varying the coupling between said conductors sufficiently to produce complete neutralization of said capacity.

3. An amplifier comprising a pair of electron discharge tubes each including an anode and a control grid, push-pull input and output circuits therefor having inter-electrode capacity requiring to be neutralized, a pair of inter-electrode capacity neutralizing circuits each connected between a grid of one tube and an anode of the other tube, neutralizing capacitance means in said neutralizing circuits providing approximately the re-

actance required for said neutralization, each of said neutralizing circuits including a conductor, said conductors having portions thereof inductively coupled, and means for varying the coupling between said portions sufficiently to produce complete neutralization of said capacity.

4. An amplifier comprising a pair of electron discharge tubes each including an anode and a control grid, push-pull input and output circuits therefor having inter-electrode capacity requiring to be neutralized, a pair of inter-electrode capacity neutralizing circuits each connected between a grid of one tube and an anode of the other tube, each of said neutralizing circuits including a conductor and a neutralizing condenser, said condensers providing approximately the reactance required for said neutralization, said conductors having portions thereof inductively coupled, and means for varying the coupling between said conductor portions sufficiently to produce complete neutralization of said capacity.

5. An amplifier comprising a pair of electron discharge tubes each including an anode and a control grid, push-pull input and output circuits therefor, and means for neutralizing the effect of the inter-electrode coupling between said input and output circuits, said means including a pair of inter-electrode capacity neutralizing circuits each connected between a grid of one tube and an anode of the other tube, said last named circuits each including a conductor and a condenser, said condensers providing approximately the reactance required for said neutralization, said conductors being inductively coupled, and means for varying the coupling between said conductors sufficiently to neutralize completely said effect.

6. An amplifier comprising a pair of electron discharge tubes each including an anode and a control grid, push-pull input and output circuits therefor having capacity therebetween requiring to be neutralized, a pair of inter-electrode capacity neutralizing circuits each connected between a grid of one tube and an anode of the other tube, each of said neutralizing circuits including a conductor and a condenser, said condenser providing approximately the reactance required for said neutralization, said conductors having portions directly inductively coupled, and means to move a portion of one of said conductors with respect to the corresponding portion of the other conductor sufficiently to produce complete neutralization of said capacity.
